UNITED STATES PATENT OFFICE.

IRWIN E. PRATT, OF LOS ANGELES, CALIFORNIA, ASSIGNOR OF ONE-HALF TO SAMUEL A. GREENWOOD, OF LOS ANGELES, CALIFORNIA.

COMBINED PAD AND HOLDER.

Application filed December 29, 1921. Serial No. 525,663.

To all whom it may concern:

Be it known that I, IRWIN E. PRATT, a citizen of the United States, residing at Los Angeles, in the county of Los Angeles 5 and State of California, have invented new and useful Improvements in Combined Pads and Holders, of which the following is a specification.

My invention relates to scratch pads, writing tablets and the like, and a purpose of 10 my invention is the provision of a combined pad and holder therefor by means of which the several leaves of the pad are securely held in pad formation and at the same time 15 permitting of the successive use and removal of the leaves.

I will describe one form of pad and three forms of holders all embodying my invention and will then point out the novel features 20 thereof in claims.

In the accompanying drawings,

Figure 1 is a view showing in perspective one form of pad and holder embodying my invention.

25 Fig. 2 is a transverse sectional view taken on the line 2—2 of Fig. 1.

Fig. 3 is a sectional view taken on the line 3—3 of Fig. 2 with the pad removed.

Fig. 4 is a fragmentary section taken on 30 the line 4—4 of Fig. 3 with the pad in applied position.

Fig. 5 is a vertical sectional view of a modified form of holder in applied position with respect to the pad and a desk blotter.

35 Fig. 6 is a view showing in side elevation another form of holder embodying my invention in applied position with respect to the portable telephone pedestal and the pad shown in the preceding views.

40 Similar reference characters refer to similar parts in each of the several views.

Referring specifically to the drawings and 45 particularly to Fig. 1, my invention in its present embodiment is shown as including a pad P made up of a plurality of leaves of equal size and secured in pad formation by means of binding elements S formed of rubber or other suitable compressible material which are associated with the sides 50 of the pad either with or without the use of adhesive material. In the latter instance, the binding elements cooperate with the holder H, which, as clearly shown in Fig. 2, comprises in the present instance a horizontal or intermediate portion 15 and ver-

tical or end portions 16, the holder as a unit being of substantially U formation and constructed of a single length of resilient metal. As shown in Fig. 3, the vertical portions 16 are each outstruck to provide upon its inner 60 side downwardly extending spurs 17 and vertically arranged securing ribs 18.

In the applied position of the holder H to the pad P as shown in Figs. 1 and 2, the spurs 17 engage the binding elements S to 65 prevent upward displacement of the elements from the holder, while the ribs 18 are likewise embedded in the elements to prevent longitudinal movement of the elements within the holder. 70

When not employing adhesive material for securing the binding elements to the pad, a pad is employed which is of a width slightly exceeding the distance between the binding elements S so that in applying the pad 75 to the holder the end portions 16 are slightly expanded and the binding elements slightly compressed. Therefore, with the pad in applied position in the holder, the leaves comprising the pad are frictionally secured 80 in the holder under the expansion action of the binding elements. It will be understood that the binding action is such that the single removal of the leaves can be readily effected. 85

Referring now to Fig. 5, I have here shown another form of holder designated generally at H' and which is of the same construction as the holder H with the exception that the horizontal portion 15 is 90 split and outstruck to provide securing fingers 19 which are arranged in pairs with the fingers of each pair bent inwardly toward each other so that they co-act in effecting the secure gripping of an element B. The element B in the present instance is a desk blotter provided with suitable openings through which the vertical portions 16 of the holder H' are extended so that the springs 17 and ribs 100 18 are disposed above the blotter. Other openings are also formed in the blotter B through which the securing fingers 19 are extended, so that after such fingers are bent in the manner shown they serve to securely 105 retain the holder as a unit upon the blotter. The pad P is retained within the holder H' in the same manner, that is to say, the spurs and ribs of the holder engage the rubber strips S with the leaves of the pad 110

glued to the strips. As the holder H is fixed within the blotter B it will be clear that the pad is securely retained on the blotter and in convenient position for ready use.

5 Referring to Fig. 6, I have herein shown another form of holder designated at H^2 and which is of the same construction as the holder H with the exception that one of the vertical portions 16 is provided with 10 an L-shaped extension 20 adapted to have the horizontal portion thereof disposed between the base 21 and the base plate 22 of a portable telephone pedestal thereby causing the holder H to securely retain the pad 15 P in convenient position upon the telephone pedestal.

Although I have herein shown and described only one form of pad and three forms of holders all embodying my invention, it is to be understood that various changes and modifications may be made herein without departing from the spirit of

the invention and the spirit and scope of the appended claims.

What I claim is:

1. A holder for pads comprising a single length of metal bent in the form of a U and having the parallel portions thereof split and outstruck to provide spurs adapted for retaining a pad against displacement from the holder in one direction, and ribs adapted for preventing the displacement of a pad from the holder in another direction. 25

2. In combination, a pad including relatively soft strips of material and adhesively secured to the pad, a holder embracing the pad, means carried by the holder and engageable with the strips for locking the pad within the holder, and an extension formed in the holder and adapted to be clamped 30 35 for supporting the holder and pad.

In testimony whereof I have signed my name to this specification.

IRWIN E. PRATT.
